3 Claims

ABSTRACT OF THE DISCLOSURE

Compounds of the class of 1-[p-carbamoylethyl-15 phenylsulfonyl]-2-imino-imidazolidines and the pharmaceutically acceptable acid addition salts thereof have hypoglycemic activity; the compounds are active ingredients of pharmaceutical compositions and can be used for the treatment of diabetes; and illustrative embodiment is 1-[p-[2 - (propylcarbamoyl) - ethyl] - phenylsulfonyl]-2-imino-3-sec.butyl-imidazolidine.

The present invention relates to derivatives of 1-[p-carbamoylethyl-phenylsulfonyl]-2-imino - imidazolidines, to pharmaceutical compositions containing these compounds and to the use thereof.

More particularly, the present invention relates to compounds of formula

wherein

R₁ is alkyl having at most six carbon atoms, cycloalkyl having from five to nine carbon atoms, allyl or benzyl; R₂ is hydrogen, methyl or ethyl; R₃ is hydrogen or alkyl having at most four carbon atoms; R₄ is hydrogen or methyl; or R₃ and R₄ together are pentamethylene;

and the pharmaceutically acceptable acid addition salts thereof.

These compounds have been found to have a hypoglycemic effect in warm-blooded animals upon oral or parenteral administration. This activity, in combination with a favourable therapeutic index, characterizes the compounds of the present invention as being suitable for the treatment of diabetes mellitus.

The hypoglycemic action can be demonstrated in standard tests on experimental animals.

In the compounds of Formula I, R₁ as alkyl, can be the methyl, ethyl, propyl, isopropyl, butyl, sec.butyl, tert.butyl, isobutyl, pentyl, isopentyl, 2,2-dimethylpropyl, 1-methylbutyl, 1-ethylpropyl, 1,2-dimethylpropyl, 1,2-dimethylbutyl or the hexyl group; as cycloalkyl, R₁ can be the cyclopentyl, 2- and 4-methylcyclohexyl, cyclohexyl,

2

cycloheptyl, cyclooctyl or trimethylcyclohexyl group, such as, e.g. the 3,3,5-trimethylcyclohexyl group.

The substituent R₃, as the alkyl group, can be anyone of the alkyl groups listed under R₁ having at most 4 carbon atoms.

Using the process according to the invention, compounds of Formula I are produced by reacting a reactive functional derivative of a sulfonic acid of formula

wherein

R₃ and R₄ have the meaning given under Formula I, with a compound of formula

wherein

R₁ and R₂ have the meaning given under Formula I; and optionally, converting the reaction product with an inorganic or organic acid into an addition salt.

A suitable functional derivative of a sulfonic acid of Formula II is, e.g. halide, especially a chloride, or also 30 an anhydride of formula

35 The reaction is performed preferably in the presence of an inert organic solvent which is miscible or non-miscible with water, in the presence or absence of water. Suitable inert organic solvents, for example, are hydrocarbons such as benzene, toluene or xylene, ethereal liquids such as ether, dioxane or tetrahydrofuran, chlorinated hydrocarbons such as methylene chloride, and lower ketones such as acetone or methyl ethyl ketone. It is advantageous to add an acid-binding agent to the reaction solution. Suitable acid-binding agents are, e.g. inorganic bases or salts, e.g. alkali metal hydroxides, alkali metal hydrogen carbonates, alkali metal carbonates or alkali metal phosphates, such as the corresponding sodium or potassium compounds. It is also possible to use organic bases such as, e.g. pyridine, trimethylamine or triethylamine, N,N-diisopropylethylamine or collidine, which, added in excess, may also be used as solvent.

40 Starting materials of Formula II are, e.g. such compounds of which the substituents R₃ and R₄ have the meaning as listed under Formula I. Such starting materials, sulfonyl chlorides, can be produced, e.g. by reacting hydrocinnamic acid amides with chlorosulfonic acid.

45 Hydrocinnamic acid amides are produced, e.g. by starting with hydrocinnamic acid chloride which can be produced, according to Mohr, *Journal für praktische Chemie* (Journal for practical Chemistry) [2] 71, 322 (1905), from hydrocinnamic acid and thiophenyl chloride. From hy-

drocinnamic acid chloride and methylamine in the presence of potassium hydroxide solution is obtained, according to Taverne, Rec. trav. chim. Pay-Bas 16, 39 (1897), hydrocinnamic acid methylamide. Other hydrocinnamic acid amides used according to the invention are produced analogously using corresponding amines.

The salts of compounds of Formula I, are produced, e.g. by reaction of these compounds with the equivalent amount of an acid in a suitable aqueous-organic or organic solvent such as, e.g. methanol, ethanol, diethyl ether, chloroform or methylene chloride.

For application as medicaments it is possible to use, instead of the free compounds of Formula I, pharmaceutically acceptable salts thereof with acids. Suitable addition salts are, e.g. salts with hydrochloric acid, hydrobromic acid, sulfuric acid, phosphoric acid, methanesulfonic acid, ethanesulfonic acid, β -hydroxyethanesulfonic acid, acetic acid, lactic acid, oxalic acid, succinic acid, fumaric acid, maleic acid, malic acid, tartaric acid, citric acid, salicylic acid, phenylacetic acid, mandelic acid and embonic acid; as well as salts with hypoglycemic sulfonyl ureas, such as, e.g. p-toluenesulfonylbutyl urea, p-chlorobenzenesulfonylpropyl urea, p-[2-(2-methoxy-5-chlorobenzamido)-ethyl]-phenylsulfonylcyclohexyl urea.

For their intended use, the compounds of the invention are administered in amounts depending on the species, the age, weight and the particular condition of the individuals being treated, and the mode of administration. In general, the daily dosage varies between about 0.1 and 100 mg./kg. of body weight for warm-blooded animals. Suitable dosage units such as dragées or tablets, contain preferably 10-500 mg. of an active substance according to the invention, i.e. 20 to 80% of a compound of Formula I.

They are produced by combining the active substance, e.g. with solid pulverulent carriers such as lactose, saccharose, sorbitol, mannitol; starches such as potato starch, maize starch or amylopectin, also laminaria powder or citrus pulp powder; cellulose derivatives or gelatine, optionally with the addition of lubricants such as magnesium or calcium stearate, or polyethylene glycols, to form tablets or dragée cores. The latter are coated, e.g. with concentrated sugar solutions which can also contain, e.g. gum arabic, talcum and/or titanium dioxide; or they are coated with a lacquer dissolved in readily volatile organic solvents or solvent mixtures. Dyestuffs may be added to these coatings, e.g. for identification of the various dosage amounts.

Further suitable dosage units for oral administration are hard gelatin capsules, as well as soft closed capsules made from gelatine and a softener, such as glycerin. The hard capsules contain the active substance preferably as a granulate, e.g. in admixture with fillers such as maize starch, and/or lubricants such as talcum or magnesium stearate, and optionally stabilisers such as sodium metabisulphite ($\text{Na}_2\text{S}_2\text{O}_5$) or ascorbic acid. In soft capsules, the active substance is preferably dissolved or suspended in suitable liquids such as liquid polyethylene glycols, whereby likewise stabilisers can be added.

The following prescriptions serve to further illustrate the preparation of tablets and dragées.

(a) An amount of 1000 g. of 1-[p-[2-(propylcarbamoyl)-ethyl]-phenylsulphonyl]-2-imino-3-cyclohexyl-imidazolidine is mixed with 500 g. of lactose and 270 g. of potato starch; the mixture is moistened with an aqueous solution of 8.0 g. of gelatine, and then granulated through a sieve. After drying of the granulate, 60.0 g. of potato starch, 60.0 g. of colloidal silicon dioxide are mixed in; the mixture is subsequently pressed to form 10,000 tablets each weighing 200 mg. and each containing 100 mg. of active substance. Optionally, the tablets can be provided with grooves to facilitate a more precise adjustment of the dosage amount.

(b) A granulate is produced from 1000 g. of 1-[p-[2-(propylcarbamoyl)-ethyl]-phenylsulphonyl]-2-imino-3-cyclohexyl-imidazolidine, 345.0 g. of lactose, and the aqueous solution of 6.0 g. of gelatine; the granulate is then mixed, after being dried, with 10.0 g. of colloidal silicon dioxide, 40.0 g. of talcum, 40.0 g. of potato starch and 5.0 g. of magnesium stearate; and this mixture is then pressed to form 10,000 dragée cores. These are subsequently coated with a concentrated syrup made from 533.0 g. of crystallized saccharose, 20.0 g. of shellac, 75.0 g. of gum arabic, 250 g. of talcum, 20 g. of colloidal silicon dioxide and 1.5 g. of dyestuff; and then dried. The obtained dragées each weight 240 mg. and each contain 100 mg. of active substance.

The following examples further illustrate production of the new compounds of Formula I, and of intermediate products not described hitherto; the examples, however, in no way constitute the only embodiments thereof. The temperatures are given in degrees centigrade.

EXAMPLE I

(a) An amount of 17.7 g. 1-sec.butyl-2-imino-imidazolidine hydrochloride is dissolved in 100 ml. of water; to this solution is then added a solution of 29.0 g. of N-propyl-p-chlorosulphonyl-hydrocinnamide in 150 ml. of acetone. To the obtained solution is added dropwise a solution of 8 g. of sodium hydroxide in 35 ml. of water, thereby the temperature is not to exceed 35°. After this dropwise addition, stirring proceeds for a further 15 minutes at room temperature, after which the solution is refluxed for 2 hours. The acetone is evaporated off in vacuo, and the precipitated oil extracted with methylene chloride. The organic phase is separated, washed with water, dried with sodium sulphate, and concentrated by evaporation. The residue is recrystallised from ethyl acetate, and 1-[p-[2-(propylcarbamoyl)-ethyl]-phenylsulphonyl]-2-imino-3-sec.butyl-imidazolidine is obtained, which melts at 111-113°.

The following are obtained in an analogous manner: From 19.0 g. of 1-cyclopentyl-2-imino-imidazolidine hydrochloride and 29.0 g. of N-n-propyl-p-chlorosulphonyl-hydrocinnamide is obtained:

1-[p-[2-(n-propylcarbamoyl)-ethyl]-phenylsulphonyl]-2-imino-3-cyclopentyl-imidazolidine, M.P. 144-146° from ethyl acetate;

From 20.4 g. of 1-cyclohexyl-2-imino-imidazolidine hydrochloride and 29.0 g. of N-n-propyl-p-chlorosulphonyl-hydrocinnamide is obtained:

1-[p-[2-(n-propylcarbamoyl)-ethyl]-phenylsulphonyl]-2-imino-3-cyclohexyl-imidazolidine, M.P. 147-149° from ethyl acetate;

From 21.8 g. of 1-cycloheptyl-2-imino-imidazoline hydrochloride and 29.0 g. of N-n-propyl-p-chlorosulphonyl-hydrocinnamide is obtained:

1-[p-[2-(n-propylcarbamoyl)-ethyl]-phenylsulphonyl]-2-imino-3-cycloheptyl-imidazolidine, M.P. 144-146° from ethyl acetate;

From 17.8 of 1-isobutyl-2-imino-imidazolidine hydrochloride and 29.0 g. of N-n-propyl-p-chlorosulphonyl-hydrocinnamide is obtained:

1-[p-[2-(n-propylcarbamoyl)-ethyl]-phenylsulphonyl]-2-imino-3-isobutyl-imidazolidine, M.P. 108-111° from ethyl acetate/cyclohexane;

From 21.8 g. of 1-(4-methylcyclohexyl)-2-imino-imidazolidine hydrochloride and 26.2 g. of N-methyl-p-chlorosulphonyl-hydrocinnamide is obtained:

1-[p-[2-(n-butylcarbamoyl)-ethyl]-phenylsulphonyl]-2-imino-3-(4-methylcyclohexyl)-imidazolidine, M.P. 167-168.5° from ethyl acetate;

5

From 24.6 g. of 1-(3,3,5-trimethylcyclohexyl)-2-imino-imidazolidine hydrochloride and 26.2 g. of N-methyl-p-chlorosulphonyl-hydrocinnamamide is obtained:

1 - [p-[2 - (n-propylcarbamoyl)-ethyl]phenylsulphonyl]-2 - imino-3-(3,3,5 - trimethylcyclohexyl)-imidazolidine, M.P. 147-148° from ethyl acetate;

From 26.8 g. of 1-(p-isopropyl-1-phenylethyl)-2-imino-imidazolidine hydrochloride and 26.2 g. of N-methyl-p-chlorosulphonyl-hydrocinnamamide is obtained:

1 - [p-[2 - (n-propylcarbamoyl)-ethyl]phenylsulphonyl]-2 - imino - 3 - (p-isopropyl- α -methylbenzyl)-imidazolidine, M.P. 151-152° from ethyl acetate;

From 21.8 g. of 1-(4-methylcyclohexyl)-2-imino-imidazolidine hydrochloride and 30.4 g. of N-isobutyl-p-chlorosulphonyl-hydrocinnamamide is obtained:

1 - [p-[2 - (n-propylcarbamoyl)-ethyl]phenylsulphonyl]-2-imino - 3 - (4-methylcyclohexyl)-imidazolidine, M.P. 158-159° from ethyl acetate;

From 20.6 g. of 1-(1,2-dimethyl)-2-imino-imidazolidine hydrochloride and 30.4 g. of N-isobutyl-p-chlorosulphonyl-hydrocinnamamide is obtained:

1 - [p-[2 - (n-propylcarbamoyl)-ethyl]phenylsulphonyl]-2 - imino-3-(1,2 - dimethylbutyl)-imidazolidine, M.P. 118-122° from ethyl acetate;

From 17.8 g. of 1-isobutyl-2-imino-imidazolidine hydrochloride and 30.4 g. of N-isobutyl-p-chlorosulphonyl-hydrocinnamamide is obtained:

1 - [p-[2 - (n-isobutylcarbamoyl)ethyl]phenylsulphonyl]-2-imino-3-isobutyl-imidazolidine, M.P. 131-133° from methyl ethyl ketone;

From 24.6 g. of 1 - (3,3,5 - trimethylcyclohexyl)-2-imino-imidazolidine hydrochloride and 30.4 g. of N-isobutyl-p-chlorosulphonyl-hydrocinnamamide is obtained:

1 - [p-[2 - (n-propylcarbamoyl)-ethyl]phenylsulphonyl]-2-imino - 3 - (3,3,5-trimethylcyclohexyl)-imidazolidine, M.P. 151-153° from ethyl acetate;

From 19.0 g. of 1-cyclopentyl-2-imino-imidazolidine hydrochloride and 30.4 g. of N-n-butyl-p-chlorosulphonyl-hydrocinnamamide is obtained:

1 - [p-[2 - (n-butylcarbamoyl)-ethyl]phenylsulphonyl]-2-imino - 3 - cyclopentyl-imidazolidine, M.P. 139-141° from ethyl acetate;

From 20.6 g. of 1-(1,2-dimethylbutyl)-2-imino-imidazolidine hydrochloride and 30.4 g. of N-n-butyl-p-chlorosulphonyl-hydrocinnamamide is obtained:

1 - [p - [2 - butylcarbamoyl] - ethyl]phenylsulphonyl]-2-imino - 3 - (1,2-dimethylbutyl)-imidazolidine, M.P. 123-125° from ethyl acetate;

From 20.4 g. of 1-cyclohexyl-2-imino-imidazolidine hydrochloride and 30.4 g. of N-n-butyl-p-chlorosulphonyl-hydrocinnamamide is obtained:

1 - [p-[2 - (butylcarbamoyl)-ethyl]phenylsulphonyl]-2-imino - 3 - cyclohexyl-imidazolidine, M.P. 161-163° from acetone;

From 21.8 g. of 1-(2-methylcyclohexyl)-2-imino-imidazolidine hydrochloride and 30.4 g. of N-n-butyl-p-chlorosulphonyl-hydrocinnamamide is obtained:

1-[p-[2-(butylcarbamoyl) - ethyl]phenylsulphonyl] - 2 - imino-3-(2 - methylcyclohexyl) - imidazolidine, M.P. 144-146° from acetone;

From 21.8 g. of 1-(2-methylcyclohexyl)-2-imino-imidazolidine hydrochloride and 27.6 g. of N-ethyl-p-chloro-

6

sulphonyl-hydrocinnamamide is obtained: 1-[p-[2-(ethylcarbamoyl)-ethyl] - phenylsulphonyl] - 2 - imino-3-(2-methylcyclohexyl)-imidazolidine, M.P. 165-167° from acetone;

From 13.8 g. of 1-methyl-2-imino-imidazolidine hydrochloride and 27.6 g. of N-ethyl-p-chlorosulphonyl-hydrocinnamamide is obtained:

1-[p-[2-(ethylcarbamoyl)ethyl] - phenylsulphonyl] - 2-imino-3-methyl-imidazolidine, M.P. 95-97° from ethyl acetate.

(b) The N-propyl-p-chlorosulphonyl - hydrocinnamamide used as starting product is produced in the following manner:

An amount of 19.1 g. of N-propyl-hydrocinnamamide, M.P. 52-54°, is added in portions, with stirring, to 35 ml. of chlorosulphonic acid. The mixture is afterwards stirred for 3 hours at 60°, whereupon it is poured on to ice. The precipitated product is extracted with chloroform. The organic phase is washed with water, dried with sodium sulphate, filtered, and concentrated by evaporation. The residue, N-propyl-p-chlorosulphonyl-hydrocinnamamide, is further used, as oil, in the crude condition.

The following are obtained in an analogous manner:

From 16.3 g. of N-methyl-hydrocinnamamide, M.P. 25-30°, is obtained: N-methyl-p-chlorosulphonyl-hydrocinnamamide, M.P. 219-221° from acetone/water;

From 20.5 g. of N-isobutyl-hydrocinnamamide, M.P. 58-61°, is obtained: N-isobutyl-p-chlorosulphonyl-hydrocinnamamide, which is further used, as oil, in the crude state;

From 20.5 g. of N-n-butyl-hydrocinnamamide, M.P. 25°, is obtained: N-n-butyl-p-chlorosulphonyl-hydrocinnamamide, which is further used, as oil, in the crude state;

From 17.7 g. of N-ethyl-hydrocinnamamide, M.P. 58-60°, is obtained: N-ethyl-p-chlorosulphonyl-hydrocinnamamide, which is further used, as oil, in the crude state.

EXAMPLE 2

Analogously to Example 1(a) are obtained:

From 20.6 g. 1-n-butyl-2-imino-5-ethyl-imidazolidine-hydrochloride and 31.8 g. N-n-butyl-N-methyl-p-chlorosulphonyl-hydrocinnamamide, 1-[p-[2-(N-n-methyl - carbamoyl)-ethyl]phenylsulfonyl] - 2 - imino-3-n-butyl-4-ethyl-imidazolidine as an oil.

From 21.8 g. 1-cyclohexyl-2-imino-5-methyl-imidazolidine-hydrochloride and 31.8 g. N-n-butyl-N-methyl-p-chlorosulphonyl-hydrocinnamamide, 1-[p-[2-(N-n-butyl - N-methyl-carbamoyl)-ethyl]phenylsulfonyl]-2-imino - 3-n-butyl-4-imidazolidine as an oil.

From 16.2 1-allyl-2-imino-imidazolidine-hydrochloride and 31.6 g. N,N-pentamethylene-p-chlorosulfonyl-hydrocinnamamide, 1-[p-[2-(N,N-pentamethylene - carbamoyl)-ethyl]phenylsulfonyl]-2-imino-3-allyl - imidazolidine M.P. 89-91°.

From 21.2 g. 1-benzyl-2-imino-imidazolidine-hydrochloride and 31.6 g. N,N-pentamethylene-p-chlorosulfonyl-hydrocinnamamide, 1-[p-[2-(N,N-pentamethylene-carbamoyl)-ethyl]phenylsulfonyl]-2 - imino-3-benzyl-imidazolidine M.P. 88-90°.

From 20.4 g. 1-cyclohexyl-2-imino-imidazolidine-hydrochloride and 31.6 g. N,N-pentamethylene-p-chlorosulfonyl-hydrocinnamamide, 1-[p-[2-(N,N-pentamethylene-carbamoyl)-ethyl]phenylsulfonyl]-2 - imino - 3 - cyclohexyl-imidazolidine M.P. 108-110°.

From 21.8 g. 1-cyclohexyl-2-imino-5-methyl-imidazolidine-hydrochloride and 31.6 g. N,N-pentamethylene-p-chlorosulfonyl-hydrocinnamamide 1-[p-[2-(N,N-pentamethylene-carbamoyl)-ethyl]phenylsulfonyl]-2 - imino-3-cyclohexyl-4-methyl-imidazolidine, M.P. 109-110°.

The N-substituted chlorosulfonyl-hydrocinnamamides used as starting materials can be obtained analogously to Example 1(b).

What is claimed is:

1. A compound of formula

wherein

R₁ is alkyl of at most six carbon atoms, cycloalkyl or methyl substituted cycloalkyl of from five to nine carbon atoms, allyl or benzyl;

R₂ is hydrogen, methyl or ethyl;

R₃ is alkyl of at most four carbon atoms;

R₄ is hydrogen or methyl; or

R₃ and R₄ together are pentamethylene;

or the pharmaceutically acceptable acid addition salts thereof.

5 2. A compound according to claim 1, which is 1-[p-[2-(propylcarbamoyl)-ethyl]-phenylsulfonyl] - 2 - imino-3-sec.butyl-imidazolidine.

3. A compound according to claim 1, which is, 1-[p-[2-(n-butylcarbamoyl)-ethyl]-phenylsulfonyl] - 2 - imino-3-cyclopentyl-imidazolidine.
